UNITED STATES PATENT OFFICE.

EDWIN CALDWELL, OF NEW YORK, N. Y.

ASH-TRAY FIXTURE.

Application filed December 15, 1924. Serial No. 755,920.

This invention relates to smokers' novelties and articles, and particularly to supports for cigars, cigarettes, and pipes, which may be advantageously utilized in connection with ash trays and the like. The invention is in the nature of an improvement upon the support disclosed and claimed in my prior copending applications #688,830, filed January 26th, 1924; #695,896, filed 10 February 29th, 1924, and #738,597, filed September 19th, 1924.

An object of the invention is to provide an improved article of this type which may be utilized in connection with ash trays of 15 the various sizes, shapes and materials, and having means for the support of cigars, cigarettes, pipes, match boxes, etc., in such a manner that the lighted ends of cigars, or cigarettes supported thereby will always extend over the open face of the tray, and the pipe bowl supported thereby will always remain in an upright position over the open face of the tray, thus preventing any fire hazard. 20

25 A further object is to provide an improved article of this type which will always support the cigars, cigarettes and pipes with the end to be placed in the mouth out of contact with all surfaces; which will 30 support cigarettes in such a manner that they will be extinguished before burning far enough to release themselves; with which the trays may be readily separated from the article for cleaning or renewal 35 purposes; which may be formed in various pleasing and artistic designs; and which will be convenient, simple, durable and relatively inexpensive.

40 A further object is to provide an improved article of this type which may be made largely from stamped sheet metal and/or bent wire in various forms and designs.

45 Various other objects and advantages will be apparent from the following description of several embodiments of the invention, and the novel features will be particularly pointed out hereinafter in connection with the appended claims.

50 In the accompanying drawings:—

Fig. 1 is a plan of a tray supported in a fixture constructed in accordance with the invention;

Fig. 2 is a side elevation of the same;

55 Fig. 3 is a sectional elevation of a portion of the fixture with the section taken

substantially along the line 3—3 of Fig. 1; Fig. 4 is a side elevation of a tray supported in a modified fixture which is also constructed in accordance with the invention; 60

Fig. 5 is a plan of the same with the accessory parts removed;

Fig. 6 is a side elevation of a fixture somewhat similar to that shown in Fig. 4, but 65 illustrating a modification thereof;

Fig. 7 is a side elevation of another fixture somewhat similar to that shown in Fig. 4, but illustrating a different type of cigar and cigarette rest attached to the body of 70 the fixture in a slightly different manner from that previously illustrated;

Fig. 8 is a plan of the same;

Fig. 9 is a side elevation of another embodiment of the fixture; 75

Fig. 10 is a side elevation of a portion of another modification of the fixture;

Fig. 11 is a side elevation of still another embodiment of the fixture; and

Fig. 12 is a plan of the fixture and tray 80 shown in Fig. 11.

Referring particularly to the embodiment of the invention illustrated in Figs. 1 to 3, the fixture extends under, and up the diametrically opposite sides of, the tray A, being detachably connected at the upper ends by a member which extends over the open face of the tray. The fixture comprises a strap 1, stamped from sheet metal, having a circular base portion 2 upon which the bottom of the tray rests, and radially extending arms 3 upon diametrically opposite sides of the base portion 2, the two radially extending arms 3 at each side of the base portion being connected at their 95 free ends by a bar 4. The arms 3 extend up the curved sides of the tray and the cross-connecting bar 4 therefor is disposed along the upper open edge of the tray.

From one of the cross bars 4, a tongue 5 100 extends upwardly and vertically in approximately the same plane for a distance approximately equal to or slightly greater than the depth of the tray, and then is bent horizontally, as at 6, in a direction to extend over the open face of the tray. The inner or free end of the angular end 6 of the tongue is rolled upon itself, as at 7, to form a hinge for a closed elongated wire loop 8 which extends over the open face of the 105 tray and interlocks with the fixture at the opposite side, as will now be explained.

A tongue 9, similar to 5, extends upwardly from the cross bar 4 at the other side of the fixture, and has an angular horizontal end 10, extending toward the end 6 and having at its free end an aperture 11 into which the free end of the wire loop 8 hooks. The free end of the loop has stretches 12 extending toward one another, and then offset downwardly to form a hook end 13 which passes through the aperture 11 in order to connect the two sides of the fixture. The loop 8 is of such a length that when it connects the opposite sides of the fixture, the tongues 5 and 9 will be sprung slightly toward one another so as to hold the opposite sides of the fixture against the opposite sides of the tray and also provide sufficient resiliency to hold the loop tightly latched in the aperture 11. To prevent accidental disengagement of the loop hook, the hook end 13 is notched as at 14 so as to snap resiliently beneath the horizontal end 10 of the tongue 9. In forcing the loop latch into the aperture 11, the tongues 5 and 9 will spring or flex to some extent and also the hook end of the loop will flex somewhat, with the result that the fixture will closely embrace the opposite sides of the tray and hold it against rocking or rattling in the fixture.

In order to confine the tray to the lower part of the fixture, the tongues 5 and 9 may have slight projections 15 struck inwardly therefrom at such points that when the tray is placed upon the bottom part of the fixture and the two opposite tongues 5 and 9 are connected by the loop 8, the projections 15 will slightly overlie the upper edge of the tray. The base portion 2 may have three or more concave domes or protuberances 2^a punched downwardly therefrom to serve as spaced points of support which will not scratch a surface upon which the fixture may be placed.

To remove the tray, it is merely necessary to unlatch the loop 8 and permit the opposite sides of the fixture to spring apart slightly, whereupon the tray A may be lifted upwardly against the underfaces of the angular ends 6 and 10, and then moved laterally from beneath these angular ends. To permit of this removal, the angular ends 6 and 10 are placed above the cross bars 4 at least a distance equal to the depth of the tray, as before explained. Where the trays are made of glass, the base portions 2 may have various designs stamped therein, such as the radially arranged openings 16^a, forming a rosette pattern, or artistically ornamented felt pads may be disposed upon the base portion 2 with the patterns or ornamentations visible through the bottom of the tray.

Each angular end 6 or 10 of the tongues 5 and 9 is provided with spaced parallel

slots 16 and the metal between the apertures is struck upwardly to form a loop strap 17, beneath which strap anchoring tongues of various accessory parts may be passed for anchorage purposes. These various accessory parts may be of various kinds, and interchangeable to suit the particular fancy of the purchaser, but in Figs. 1 to 3, two different accessory devices are illustrated by way of example.

Upon the angular or horizontal end 6 of the tongue 5, a combined cigar and cigarette support 18 is mounted. This combined support is stamped from sheet metal, with its ends bent angularly to the body portion and divergent relatively to one another. From the interior of the body of the support, a tongue 19 is struck out, with an aperture 20 surrounding the tongue. The tongue 19 is offset downwardly slightly, so that it may be passed beneath the struck up strap or loop 17 when superposed upon the angular end 6 of the tongue 5, the tongue being slid beneath the strap 17 as the support is moved into position. This serves as a frictional and resilient connection between the combined support and the angular end 6, the base of the tongue limiting the inward movement of the support upon the angular end 6.

The outer bent end 21 of the support is provided with a concave notch 22 at its free end edge, for a purpose to appear presently. The other bent end 23 of the support is provided with a notch or slot 24 leading from the free end edge toward the base of the bent end, the notch or slot having a minimum width slightly less than the normal diameter of a cigarette, so that when a cigarette is forced into the notch, it will be slightly compressed and, therefore, frictionally gripped thereby with sufficient tightness to be supported therein.

The base or inner end of the notch 24 is preferably made slightly wider than the narrowest portion, so that when the cigarette is forced therein, it may expand slightly at the inner end of the slot and thus be more effectively and firmly anchored in the slot. The free end edge of the bent end 23 of the support is concavely beveled, as at 25, leading to the slot 24, so as to assist in guiding a cigarette into the notch 24, and also so as to serve, together with the notch, as a concave support that will cooperate with the concave notch 22 in supporting a cigar which may be placed upon the bent ends 21 and 23.

The longitudinally extending stretches of the wire loop are preferably spaced apart a distance of approximately 1 1/8 to 1 1/4 inches in order that a pipe may be supported upon the loop with the bowl resting upon the loop and the stem resting upon the inner end of the combined cigar and cigarette support,

- the pipe stem being embraced between the concave beveled edges 24 and 25 to prevent it from swinging laterally in a manner to cause tipping of the pipe. As a result, the 5 pipe will be supported in a stable position, with the bowl upright and with the mouth piece out of contact with all surfaces.
- A match box holder 26 is illustrated, by way of example, as mounted upon the other 10 tongue 9, and such a holder may be formed by stamping out an elongated strip from sheet metal and bending the same into the shape of an open ended parallelopiped, the abutting edges of the ends of the bent strip 15 being unconnected for a purpose which will appear presently. The bottom wall 27 of the holder is provided with a tongue 28 struck downwardly from its interior and adapted to slide beneath the struck up strap 20 17 upon the angular or horizontal extension 10 of the tongue 9, in the same manner that the combination cigar and cigarette holder 18 is slidably attached to the opposite tongue.
- 25 The interior of the parallelopiped is approximately equal to but slightly smaller than the periphery of a safety match box, so that when a safety match box is slid endwise into the parallelopiped, the walls of 30 the parallelopiped will separate slightly at the abutting edges and thus form a frictional grip upon the outer shell of the match box and frictionally hold it therein. While so held, the inner container of the 35 match box may be slid into and out of the outer shell and parallelopiped, in the usual manner through the open ends of the parallelopiped.
- The side walls of the parallelopiped are 40 provided with open windows or apertures 29, through which the treated or roughened striking side surfaces of the match box will be exposed for striking purposes. When the contents of the match box have been used, 45 the old box may be removed in its entirety and a new filled box substituted therefor.
- In Figs. 4 and 5 another embodiment of the invention is illustrated. In these figures a strip or ribbon 30 of sheet metal of 50 uniform width is extended beneath a tray A, diametrically thereof, and in the bottom portion is offset downwardly as at 31, the offset portion being offset upwardly slightly, as at 32, at its central point for a purpose 55 which will appear presently. The ends of the ribbon or strip 30 extend upwardly above the upper edge of the tray for a distance approximately equal to or greater than the depth of the tray, and are turned toward one 60 another, as at 33, over the open face of the tray to form supporting shelves for the various accessory parts which are permanently or detachably secured thereto.
- A second ribbon or strip 34 of sheet metal 65 is extended beneath the tray at right angles to the strip 30, and is also offset downwardly at 35 similar to the downward offset 31, and passes beneath the upper offset portion 32 of the strip 30, so that the underface of the strip 34 at the offset portion 35 will be substantially flush with the underface of the offset portion 31 of the strip 30. The upper or free ends of the strip 34 are rolled inwardly upon themselves to form beads 36 which are adapted to snap over the upper edge of the 70 tray A and yieldingly hold it against the bottom of the strips.
- A disc 37 of sheet material, such as sheet metal, is disposed in the downwardly offset sections 31 and 35 of the strips 30 and 34. 75 This disc 37 will be countersunk in the pockets formed by the offset sections 31 and 35, and may have any desired pattern struck therefrom, or it may carry other desired ornamentation, such as a felt or fabric disc 80 pad having contrasting patterns placed thereon which will be visible through the bottom of the tray when the tray is of glass.
- The strips 30 and 34 are secured together 85 and to the disc 37 in any suitable manner, such as by a rivet 38, and if the length of the offset section 32 of the strip 30 is approximately equal to the width of the ribbon strip 34, the ribbon strips 30 and 34 will be held at right angles to one another with only a single securing rivet 38.
- The strips 30 and 34 are secured together 90 and to the disc 37 in any suitable manner, such as by a rivet 38, and if the length of the offset section 32 of the strip 30 is approximately equal to the width of the ribbon strip 34, the ribbon strips 30 and 34 will be held at right angles to one another with only a single securing rivet 38.
- In order to prevent contact of the under 95 end of the rivet 38 with the surface upon which the tray and fixture may be supported, the offset portions 31 and 35 of the ribbon strips are provided with convex protuberances or domes 39 on their underfaces, which may be formed by forcing the material downwardly from the bodies of the ribbon by suitable dies. By the use of such domes 100 or protuberances, the tray and fixture will be supported solely at four points, and consequently there will not be any tendency for it to rock upon the supporting surface.
- To insert or remove the tray, it is merely 105 necessary to spring the free ends of the strip 34 apart to clear the beads 36 from the edge of the tray, whereupon the tray may be lifted until it strikes the underfaces of the angular ends 33 of the ribbon strip 110 30, and then withdrawn laterally from the fixture.
- Any of the accessory parts may be attached 115 to the extensions 33, either permanently or by means of the tongues projecting from the 120 accessory parts and sliding under the projecting straps as in the preceding embodiment.
- In Fig. 6 another embodiment of the invention is illustrated, which is somewhat 125 similar to that shown in Figs. 4 and 5, but differs therefrom only by the fact that the ribbon strip 30^a, corresponding to the ribbon 30 of Figs. 4 and 5, instead of being bent inwardly over the tray at the ends are bent 130

away from the tray as at 40, to form shelves upon which the accessory parts or devices may be mounted as in the preceding embodiments. The ends are then turned backwardly upon themselves as at 41, the extreme ends 42 being curled for ornamental purposes and also extend down to the plane of the bottom of the fixture so that, by also engaging the supporting surface upon which the fixture may rest, they will prevent tipping of the tray when pressure is applied to any of the accessory parts, such as the pressure that would be caused by the forcing of a cigarette into the slot or notch 24. This is particularly important in this embodiment of the invention because the shelves upon which the accessory parts are mounted, extend away from the tray and not over the tray and, therefore, any tipping movement, caused by the same pressure upon the accessory parts, would be greater in this embodiment because the tipping force would be applied at a greater distance from the axis of tipping. By having the ends curled or extended into contact with the supporting surface, they would resist this increased tendency to tip and thus make the tray fixture as stable as the others. These ends 42 may, if desired, be secured to the ribbon strip 30^a but in any event, the looped back portions 41 will serve as handles by which the fixture and tray may be lifted and carried about.

In Figs. 7 and 8, the illustrated fixture is similar to that shown in Figs. 4 and 5, except that instead of having the straps struck up from the faces of the shelves as in Figs. 1 and 2, the angular ends 33^a will have parallel and longitudinally extending tubular beads or straps 43 struck up from the interior thereof, or rolled from the edges to form tubular sockets. A wire support 44, formed by bending a stretch of spring wire, has its two ends brought approximately parallel and inserted into the tubular beads or sockets 43, with the body of the wire support extending over the open face of the tray.

This support is preferably formed by first bending the wire strip intermediate of its ends into a somewhat U-shape, and making the cross arm portion 45 thereof downwardly concave. The arms of the U-shaped portion are then bent intermediate of their ends toward one another and downwardly, and then as at 46 approximately parallel to the arms adjacent the cross arm 45, but slightly convergent toward the free ends which are inserted in the beads or sockets 43. The distance between the arms 46 of the wire support which enter the beads is slightly less than the diameter of a cigarette, so that a cigarette may be supported thereby by merely wedging it between the two arms 46 where they project over the tray. A cigar 65 may be supported upon the support by rest-

ing it upon the downwardly concave cross arm portion 45 and at the downwardly bent ends between the upper portion and the arms 46.

In Fig. 9 another embodiment of the invention is illustrated. In this form of the invention, two strips or ribbons 47 of sheet metal are disposed at opposite sides of the tray so as to extend under the same, but not extending entirely across the bottom face of the tray. These strips 47 are connected by arcuate bands 48 which are secured, such as by welding or riveting, at their ends, to the strips 47, these strips 48 extending from the strips 47 in opposite directions around the tray A slightly below the outer edge thereof, and form a loop of such size that the concave circular periphery of the tray will seat and be supported therein.

The upper ends of the strips 47 will extend above the open edge of the tray at least a distance equal to the depth of the tray, so that the tray may be removed by merely lifting it above the strips 48 and then moving it laterally. The ends of the strips 47 are bent toward one another over the open face of the tray, as at 49, to form shelves upon which the accessory parts, such as combined cigar and cigarette supports, or the match box, may be supported either permanently or detachably as in the preceding embodiments.

In Fig. 10, an embodiment similar to that shown in Fig. 9 is illustrated, with the exception that the lower ends of the strips 47^a, corresponding to 47 in Fig. 9, instead of extending beneath the tray are curled downwardly and backwardly upon themselves, as at 50, to form supporting feet, and the plane tangent to the extreme lower ends of the feet is preferably only slightly above the bottom face of the tray when the tray is supported therein, so that when the fixture is placed upon a surface, the bottom face of the tray will engage the surface just before the feet strike it, the tray rising in its seat a slight amount to permit the fixture to settle upon the supporting surface.

In Figs. 11 and 12 another embodiment of the idea shown in Fig. 10 is illustrated, except that the strip 51, corresponding somewhat to the strip 47^a, extends entirely across the open face of the tray. The two sections on opposite sides of the tray constitute merely the ends of this common strip. Thus the section 52 extending across the open face of the tray will tie together the supporting feet upon opposite sides of the tray and serve as a shelf upon which the various accessory parts may be mounted as in the preceding embodiments. However, the central portion of the section 52 is enlarged in the form of an open ellipse or ring 53, so as to form an opening 54 in which the base of a pipe bowl may rest and be supported, with the stem

of the pipe resting upon and supported by the accessory parts such as the cigar and cigarette supports which are attached to the cross bar section 52.

5 In all of these embodiments of the invention, it will be observed that the upwardly extending straps at the sides of the tray may be utilized as handles by which the tray and fixture may be carried about, and the tray 10 itself may be readily removed for cleaning purposes. The tray may be of glass, porcelain, metal, or of any other material, and is not necessarily permanently attached to the fixture so that broken trays may be replaced without discarding the entire device. 15 The removal feature facilitates more effective cleaning of the trays when they are separated from the fixtures.

Another advantage of this arrangement of 20 this invention, is that if the trays are made of glass, which is fragile, they may be shipped separately from the fixtures with less danger of breakage, and may also be sold separately from the fixtures if desired. 25 When assembled, the fixtures serve as a protection to some extent for the tray to prevent injury or breakage thereof. In Figs. 1 and 2, the openings formed between the arms 3 and cross bars 4 will receive the concave 30 surface of the tray and more effectively support it.

The accessory parts, such as the combination cigar and cigarette supports, and the match holders, may be either permanently 35 secured to the fixtures or may be detachably connected thereto by various schemes, such as by those illustrated, and serve to support cigars and cigarettes with their lighted ends over the open face of the tray, and also 40 to serve to support the stems of pipes when the bowls of the pipes are disposed in the wire loop 8 or over in the tray itself. By having these accessory parts detachable, the purchaser may select a combination of such 45 parts to suit his particular fancy, without the necessity of the dealer carrying excessive stocks of all kinds. This detachable feature also permits of the customer changing the accessory parts if, after a purchase, 50 a change is desired.

In the case of the combination cigar and cigarette supports, the cigarette will be extinguished before it burns far enough to release itself by reason of the cooling, 55 through conduction, of the burning tobacco before the point of burning reaches the point of contact. That is, the material of the support, which is of good heat conducting material, such as metal, will so chill the tobacco, 60 which is compressed between it that the slowly burning tobacco, in approaching it, will be chilled below the temperature of combustion and thus be extinguished.

The upper faces of the bottoms of the fixtures may, if desired, be proved with re-

silient pads to absorb shocks caused by dropping the fixture abruptly upon a supporting surface. The match box holders may extend either sideways or in a direction over the tray as desired.

70 It will be observed that these fixtures may be formed from sheet metal and bent wire, and as a result they will be relatively inexpensive, and may be given various artistic and pleasing designs.

75 It will be obvious that various changes in the details and materials, which have been herein described and illustrated for the purpose of explaining the nature of the invention, may be made by those skilled in the art 80 within the principle and scope of the invention, as expressed in the appended claims.

I claim:

1. In a fixture for ash trays comprising a frame in which an ash tray may be deposited for support, with the frame extending up the sides of the tray and having shelf portions adjacent the upper face of the tray, and smokers' accessory parts removably mounted on said shelf portions.

85 2. In smokers' novelties, a fixture for receiving and supporting an ash tray, said fixture having a shelf portion adjacent the upper face of the tray, a strap on said shelf, and a smokers' accessory part mounted on the shelf with a tongue on said part extending under the strap to serve as a connecting 95 means between the part and shelf.

3. In smokers' novelties, a fixture for ash trays comprising an elongated strip of sheet metal extending under the bottom of the tray and at its ends extending above the open face of the tray, and then over the open face of the tray to form shelves, and smokers' accessory parts mounted on said shelves.

100 4. In smokers' novelties, a fixture for ash trays comprising an elongated strip of sheet metal extending under the bottom of the tray and at its ends extending above the open face of the tray and then over the open face of the tray to form shelves, said shelf portions having guide means struck therefrom, and smokers' accessory parts having tongues struck downwardly therefrom and slidably received and supported in the guide 110 means to secure the parts to said shelves.

5. In smokers' novelties, a fixture for ash trays comprising a frame for receiving and supporting an ash tray, having tongues extending upwardly above the open face of the tray and then horizontally to form shelves, and smokers' accessory parts detachably mounted upon said shelves.

115 6. In smokers' novelties, a fixture for ash trays comprising a frame in which an ash tray is received and supported, said frame having a tongue extending upwardly from a side thereof and then horizontally to form a shelf, and a cigarette support secured to the shelf with one end extending over the 125

open face of the tray, said one end having a bent up flange carrying a notch leading from an edge thereof and of a width slightly less than the diameter of a cigarette, whereby a cigarette will be supported in said notch when wedged therein.

7. In smokers' novelties, a fixture for ash trays comprising a frame in which an ash tray is received and supported, said frame 10 having a tongue extending upwardly from a side thereof and then horizontally to form a shelf, and a cigarette support secured to the shelf with one end extending over the open face of the tray, said one end having 15 a bent up flange carrying a slot leading from an edge thereof and of a width slightly less

than the diameter of a cigarette, whereby a cigarette will be supported in said notch when wedged therein, the other end of such support having a concave notch in its upper edge, the flange with the slot also having a flared entrance to the slot which cooperates with the concave notch to support a cigar. 20

8. In smokers' novelties, a fixture for ash trays comprising a sheet metal frame in 25 which the tray may rest and be supported, said frame having guiding means struck therefrom, and a smokers' accessory part slidingly received thereby.

In witness whereof, I hereunto subscribe 30 my signature.

EDWIN CALDWELL.
